corporation of Delaware

Application June 28, 1945, Serial No. 602,115

26 Claims. (Cl. 51—165)

1

This invention relates to gauging apparatus and particularly to gauging apparatus which controls a sizing operation on a work piece.

An object of the invention is to provide an improved gauging apparatus for controlling a grinding operation on one of a pair of articles to be used in mating relation, and wherein the size of one of the articles already finished controls the grinding to size of the other article.

Another object is to provide improved gauging apparatus for controlling the grinding of a work piece to a size determined by the measured size of another work piece.

To these ends and also to improve generally upon devices of the character indicated, the invention consists in the various matters hereinafter described and claimed. In its broader aspects, the invention is not necessarily limited to the specific construction selected for illustrative purposes in the accompanying drawings wherein

Figure 1 is a diagrammatic fragmentary showing of the matched grinding control mechanism with the parts in position to effect a finish grinding operation;

Figure 2 is a front elevation of the feeding mechanism with the feeding pawls in positions to produce a finish grinding feed;

Figure 3 is a vertical section taken approximately along the line 3—3 of Figure 1;

Figure 4 is an enlarged perspective view of the valve operating members within the gauging mechanism;

Figure 5 is a fragmentary sectional view taken along the lines 5—5 of Figure 1;

Figure 6 is a fragmentary sectional view taken along the lines 6—6 of Figure 4;

Figure 7 is an enlarged sectional view showing a portion of one of the feeding control valves; and

Figure 8 is an enlarged fragmentary view of the mechanism for lifting the gauging stem.

This invention, which controls the grinding of one article to a size determined by the measured size of another article, is particularly adapted for controlling a grinding operation upon a raceway on one of a pair of race rings to be used in mating relation in an antifriction bearing. The raceway grooves for the mating race rings of ball bearings are ordinarily ground separately on oscillating grinding machines, these raceways being ground to predetermined sizes within as close limits of accuracy as the grinding machines are capable. Rolling elements of a given size are then interposed between the race rings. Due to slight inaccuracies of grinding, either one or both race-

2

way grooves may be oversize or may be undersize, and frequently these errors of grinding are cumulative. Attempts to reduce these cumulative errors have been made by gauging and matching the raceway sizes of the mating race rings so that the errors would tend to compensate each other. Also, some of these errors have been reduced by selecting the sizes of the balls which roll within the mating raceways. The additional operations of gauging and sorting race rings and balls for matching relation hinders production and often results in incorrect fit of balls within the raceways. According to the present invention, the raceways of either the outer or the inner race rings are ground in a satisfactory manner and as closely as possible to the desired finished raceway size. Thereafter, each finished raceway, irrespective of its size, is used in conjunction with my gauging apparatus to control the grinding to a corresponding size of the raceway to be used therewith in mating relation. By way of illustration, the invention is herein described by reference to the grinding of the raceway of a ball bearing inner race ring under control of the finished raceway size of the outer race ring that is to be used in mating relation with this inner race ring.

Generally considered, an outer race ring, as A, has a finished raceway B measured by a gauge 10 provided with a valve lever 12 whose position is determined by the size of the raceway B. An inner race ring, as C, provided with a raceway R to be ground by a grinding wheel 14 to a size for assembly in mating relation through standard sized bearing balls with the raceway B, is rotatably mounted in a suitable manner for grinding, as on an oscillating grinding machine. The details of this grinding machine are not herein illustrated since they may be variously constituted in accordance with standard construction. During grinding, a gauging mechanism, generally indicated at 15, has a vertically movable stem 16 that responds to the size of the raceway R and acts through an amplifying leverage and a pivoted transfer lever 18 to successively open a pair of self-closing flap valves 20 and 21 on the valve lever 12, these valves being respectively connected through ducts or hoses 22 and 23 to a pair of grinding feed controlling valves 24 and 25. A suction pump P produces a partial vacuum or less than atmospheric pressure in the hoses when the flap valves are closed. When the raceway R is ground down nearly to the final size determined by the position of the valve lever 12, an adjusting screw 27 on the advancing lever 18 opens the flap

valve 20 which admits atmospheric pressure into the hose 22 causing the feeding control valve 24 to change an initial coarse grinding feed to a finish grinding feed. When the raceway R is completely ground except for sparking out, a stud 28 (Figure 4) on the advancing arm 18 opens the flap valve 21 which admits atmospheric pressure into the hose 23 causing the valve 25 to stop the grinding wheel feed. At the completion of the grinding operation, the grinding machine is stopped and the stem 16 is lifted out of raceway engagement causing both flap valves to close. The suction pump P again produces a partial vacuum in the hoses 22 and 23 and returns the valves 24 and 25 to their initial positions which will cause a coarse feed of the grinding wheel at the start of the next grinding cycle.

In the illustrated embodiment, the gauging mechanism 10, which may be suitably supported in a fixed position above the race ring C during grinding, is provided with a ball-type gauge 30 for supporting and gauging the outer race ring A which determines the grinding to size of the raceway R. A horizontally disposed sleeve 32 axially extends through a supporting bracket 33, fastened to a side of a casing 34, and into an aperture through this casing. The sleeve 32 is slidably journaled in the ends of the bracket 33 and is threaded in this bracket at 35 for axial adjustment. The outer end of the sleeve 32 terminates in a frusto-conical head 36 which engages a series of peripherally spaced balls 37 loosely held within and extending through ball pockets 38 formed by a flanged annular member 40 and a cylindrical head 42. These balls preferably are the same size as and are spaced correspondingly to the balls which will be later assembled with the race rings A and C. The flanged annular member 40 loosely surrounds the sleeve 32, and the ball pockets have plates provided with flat wear-resistant ball engaging faces 43 located in a common plane perpendicular to the axis of the frusto-conical head 36. A rod 44, coaxial with the head 36, axially extends through and is journaled in the sleeve 32. A coiled spring 45, compressed between an end of the sleeve 32 and a collar 46 fastened on the rod 44, yieldably urges this rod into the casing to a gauging position which is determined by that axial position of this rod at which the ball engaging faces 43 uniformly urge the balls 37 upwardly on the frusto-conical head 36 and into seated engagement with the raceway B. To prevent uneven wear of the head 36 and to assure that the rod 44 is located in gauging position, the race ring A may be manually turned on the supporting balls 37.

The valve lever 12, which is pivotally supported by a pair of spring reeds 47 mounted in a block secured to the casing, is shifted by the rounded end of the rod 44 to a gauging position determined by the size of the raceway B. A spanner ring 48, fastened to the sleeve 32, has peripheral graduations adjacent to an index finger 50 on the supporting member 33 as shown in Figure 5. Rotating this spanner ring axially positions the sleeve 32 and the rod 44 to control the operating positions of the valves 20 and 21 with respect to the measured size of the raceway B. The spanner ring 48 is preferably so graduated that rotating of this ring from one graduation to the next effects a change of one ten thousandth of an inch in the size to which the raceway R is ground. A locknut 52, threaded upon the sleeve 32, may be tightened against the supporting member 33 to secure this sleeve in adjusted position. A hand

lever 53 acts through a shaft 54, projecting through a casing cover 55 and journaled in a casing bracket 56, to swing a forked depending arm of a lever 57 against the collar 46 to retract the rod 44 from gauging position which permits the balls 37 to shift laterally and radially inwardly with respect to the frusto-conical head 36 so that the race ring A may be mounted in and demounted from gauging position. An adjustable stop screw 58, extending through the upper end of the lever 57, is engageable with the bracket 56 to prevent the lever 57 from moving into interfering relation with the valve lever 12. The casing cover 55 has a window 59 through which the operator may observe the operating positions of valves 20 and 21. A filter 60 mounted in a bore through the casing cover 55 admits air to the valves 20 and 21.

The stem 16 is vertically slidable in a boss 61 at the bottom of the casing 34 and in a bushing 62 having a lower reduced portion pressed within a boss 63 secured to the top of the casing. A suitably hard gauging point 64, as a diamond, projecting from the lower end of the stem 16, rides upon the raceway R and supports the stem 16 during grinding. A coiled spring 65, compressed between the top of the casing and a collar on the stem 16, yieldably urges the stem 16 downwardly into gauging position. A collar 66, journaled on the enlarged upper portion of the bushing 62 (Figure 8) and normally seated on the top of the boss 63 has a spiral slot 67 open at its lower end and slidably engaging a pin 68 laterally projecting from the enlarged upper end of the non-rotatable bushing 62. A washer 70, loosely fitted over the upper end of the bushing 62, is normally loosely positioned between the top of the collar 66 and the underside of a cup-shaped cover 72 secured by a cap nut against a shoulder on the upper end of the stem 16. A hand lever 73, projecting through a slot 74 in the cover 72, is threaded into the collar 66. When this hand lever is swung to the position of Figures 1 and 8 to locate the pin 68 at the top of its slot 67, the stem 16 is lowered into supported relation upon the raceway R, and there is sufficient clearance between the top of the washer 70 and the underside of the cover 72 so that the stem 16 is free to move downwardly and remains supported by the raceway R during the entire grinding operation. During gauging, the hand lever 73 may be secured in position by a spring 75 mounted on the cover 72. When this hand lever is swung to the opposite end of the slot 74, the collar 66 rides upwardly on the pin 68 and acts through the washer 70 and the cover 72 to lift the stem 16 out of raceway engagement so that a race ring C may be mounted in and demounted from grinding position. To secure the stem 16 in its inoperative raised position, the hand lever 73 is swung sufficiently to remove the pin 68 from the open lower end of the slot 67 and the bottom of the collar 66 is supported by this pin.

A block 76, fastened to a lower portion of the casing 34, holds an end of each of a pair of spaced generally horizontal reed springs 77 whose other ends co-operatively support a vertically floating block 78. A block 79, fastened to the stem 16, has on its lower end a hardened contact point engaged by a laterally projecting arm 81 on the floating block 78 which is urged upwardly by a coiled spring 82 causing the floating block 78 to assume a vertical position dependent upon the vertical position of the stem 16. A pair of upwardly extending flat springs 83 and 84, whose

spaced lower ends are secured respectively to the upper ends of the blocks 76 and 78, are secured intermediate of their lengths to a spacer plate 85 and are also secured together at their upper ends. The downward movement of the stem 16 and of the floating block 78 in response to a reduction in size of the raceway R, produces a corresponding downward movement of the spring 84 while the fixed block 76 prevents a bodily downward movement of the spring 83. These springs coact as an amplifying lever wherein a slight downward movement of the spring 84 results in a greatly amplified movement of the upper ends of both springs towards the valve lever 12. An upward movement of the stem 16 out of raceway engagement produces an amplified swinging movement of the upper ends of both springs 83, 84 away from the valve lever 12 and to a stop position limited by an adjustable screw 86 threaded in the casing 34. The transfer lever 18, which is generally T-shaped with a transversely extending head 87, is pivotally supported at its lower end by a cross shaft 88, and a counterweight lever portion 90 urges this lever clockwise to a position determined by the engagement of one end of the head 87 against a stud 92 which laterally projects from the upper ends of both springs 83 and 84.

The self-closing flap valves 20 and 21, which control the operation of the grinding wheel feeding control valves 24 and 25, include a pair of spaced upwardly extending spring flaps 93 and 94 whose lower ends are rigidly fastened to the valve lever 12 and whose upper ends are arranged to be engaged respectively by the adjusting screw 27 to open the valve 20 for changing an initial coarse grinding wheel feed to a finish grinding feed, and by the stud 28 to open the valve 21 for stopping and grinding wheel feed when the raceway R is ground down to a size determined by the measured size of the raceway E. The subsequent sparking-out of the grinding wheel brings the raceway R to a final size for mating relation with the race ring A when assembled with standard sized balls. The spring flaps 93 and 94 tend to close ports 95 and 96 at the ends of valve chambers 97 and 98 to which are connected the hoses 22 and 23, these hoses having sufficient flexibility to permit positioning of the valve lever 12 by the rod 46.

The grinding wheel feeding mechanism includes a ratchet wheel 100 suitably arranged to operate a screw shaft for producing a feed of the grinding wheel 14. Pawls 102 and 103, pivotally secured at their rearward ends to an oscillating lever 104, are urged by a coiled spring 105 towards ratchet wheel engagement. The oscillating lever 104 is pivotally supported by a screw 106 carried by a frame 107, and is oscillated through an adjustable extent by a link 108 whose lower end is journaled upon a crank pin 110 having its throw adjusted by a screw 112. The crank pin 110 may be revolved by a motor or other suitable driving mechanism. Pivoted to the frame 107 at 113 is a lever 114 provided with a cam portion 115 engageable with a screw 116 adjustably threaded through a plate 117 which is fastened to and longitudinally adjustable on the pawl 102. The lever 114 also has a cam portion 118 engageable with a screw 120 adjustably threaded through a plate 122 which is secured to and longitudinally adjustable on the pawl 103. A coiled spring 124, connected to the lower end of the lever 114, urges this lever clockwise towards engagement with an adjustable stop screw 126. Latch blocks 127 and 128, laterally projecting from the lower end of

the lever 114, are respectively engageable with a latch pin 130 to initially locate the lever 114 at position 114A wherein both pawls 102 and 103 cooperatively produce the initial coarse grinding wheel feed, and with a latch pin 131 to subsequently locate this lever 114 at its full line indicated position wherein the cam portions 115 and 118 will limit the effective feeding strokes of the pawls 102 and 103 to provide a finishing feed of the grinding wheel 14. When the latch pin 131 is thereafter withdrawn from engagement with the latch block 128, the lever 114 is swung by the spring 124 to its final position 114B determined by the screw 126, and in this final lever position, the cam portions 115 and 118 hold both pawls 102, 103 out of ratchet wheel feeding positions. The grinding feed controlling valves 24 and 25 respond to the opening of the valves 20 and 21 to selectively retract the latch pins 130 and 131 from engagement with the latch plates 127 and 128 as will be later described.

A counting ratchet wheel 133 determines the number of oscillations of the grinding wheel 14 across the raceway R after the feed of the grinding wheel has been stopped. This ratchet wheel 133, which is rotatable on a stud carried by the frame 107, is urged clockwise by a torsion spring 134 that is opposed by a detent 135 pivoted at 136 and provided with a latch hook 137 normally latched under a shoulder 138 upon a head 140 fastened to the upper end of a valve stem 142 projecting from a control valve 143 which controls the starting and stopping of the oscillating mechanism of the grinding machine. A pawl 144, spring urged towards ratchet tooth engagement with the counting ratchet wheel 133, is pivotally supported by a stud 145 carried by the outer end of a link 146 whose inner end is journaled upon the stud which rotatably supports the counting ratchet wheel. A generally vertical link 147, journaled at its lower end upon the stud 145, is pivoted at its upper end to the oscillating lever 104 coaxially of the pawl 103. While the lever 114 is in either of its positions which permits the pawls 102 and 103 to produce a grinding wheel feed, a rounded upper end 148 of the pawl 144 is engaged by the lever 114, as shown, to hold the pawl 144 out of engagement with the ratchet wheel 133. When the lever 114 swings to its final position 114B to stop the grinding wheel feed, the pawl 144 is released into engagement with the counting ratchet wheel 133. The lever 104 and the links 146 and 147 angularly oscillate the pawl 144 to produce a step by step rotation of the counting ratchet wheel 133 until a trip lug 150 on an arm 152, adjustably secured to this ratchet wheel 133 by a clamp screw in a slot, lifts the detent 135 from the shoulder 138 to allow the valve stem 142 to descend and stop the grinding wheel oscillating mechanism, thereby providing for a predetermined number of grinding wheel oscillations during the sparking-out of the grinding wheel. The shifting of the valve 143 to stop the grinding wheel oscillations also operates through suitable mechanism, not shown, to rotate the ratchet wheel 100 backwardly for retracting the grinding wheel 14 from the grinding zone.

A plate 154, secured to and laterally projecting from the head 140, moves vertically with the valve stem 142 and acts through a pivoted link 155 to swing a bell crank lever 156 upon a stud mounted in the frame 107, and an upstanding arm 157 of this lever 156 operates through a pin and slot connection to position a horizontal slide 158. The slide is supported by a guide bracket 160 having

a tongue extending into a slot 162. Pivoted at 163 to the slide 158 is a lever 164 urged clockwise by a spring 165 having one end anchored by a stud on the slide. In the illustrated position, the lever 164 is held against clockwise movement by a lug 166 engaging the head of a stop screw 167 adjustably secured in a lug projecting from the frame 107. The shifting of the slide 158 towards the left, in response to a downward movement of the valve stem 142, transports the lever 164 away from the stop screw 167, and the spring 165 swings this lever clockwise to lift a lever hook 170 so that during the following movement of this slide towards the left, the lever hook 170 will latch over a pin 172 on the lever 114 which is now located in its position 114B to prevent feeding of the grinding wheel. At the start of the next grinding operation when the operator resets the valve 143 by lifting a handle 173 that projects from the head 140, the slide 158 shifts back to the right towards its illustrated position, and the lever hook 170 acts through the pin 172 to shift the lever 114 past both latch pins 130 and 131 which are now located in latching positions. Final movement of the slide 158 towards the right again engages the lug 166 against the stop screw 167 causing disengagement of the hook 170 from the pin 172 and locating the lever 114 in its coarse feed grinding position 114A and latched against the latch pin 130. During the upward movement of the valve stem 142 and the return of the lever 114 to its position 114A, the head 140 cams the detent 135 away from the ratchet wheel 133, and the torsion spring 134 returns this ratchet wheel and the trip lug 150 clockwise to their starting positions which are determined by the engagement of a ratchet wheel pin 174 against a lug 175 on the frame 107. When the valve stem 142 has been lifted to its top position, the detent 135 again drops into ratchet tooth engagement and into supporting relation for the head 140.

The grinding feed controlling valves 24 and 25 are of duplicate construction and have their corresponding parts similarly identified. The latch pins 130 and 131, which successively release the latch plates 127 and 128 to regulate the position of the feed controlling lever 114, are respectively mounted in the heads of pistons 176 slidable in cylinders 177 and urged by coiled springs 178 towards engagement with cylinder heads 180 to locate the latch pins in latching positions as shown by the positions of the parts of the grinding feeding control valve 25 in Figure 1. Each cylinder head 180 has a through port 181 to prevent trapping of air within the forwardends of the cylinders and which might hinder piston movement. Rearward valve extensions 183 each contain a passage 184 whose forward end opens into the rearward end of its cylinder, the rearward ends of these passages respectively opening into vertically aligned ports 185 and 186, these ports being provided with valve seats within the passages 184. As best illustrated in Figure 7, each port 185 has an outer end open to the atmosphere, and the lower end of each port 186 communicates with a variable sized chamber 187 located between a flexible diaphragm 188 and a wall 190, each diaphragm being sealingly clamped between the wall and a recessed cap 192 which also provides a variable sized chamber 193 beneath the diaphragm. The suction pump P is connected through piping 194 to both chambers 187, and the hoses 22 and 23 are respectively connected to the chambers 193 of the grinding feed controlling valves 24 and 25. Each of these controlling valves

also has a valve member 195 provided with a stem loosely extending downwardly through one of the ports 186 for end engagement with a wear plate 196 secured to the diaphragm. A generally cylindrical head 197 on the upper end of each valve member has flat top and bottom faces which are brought into relative valving engagement with the valve seats at the ends of the ports 185 and 186 within the passage 184 and under control of the deflection of the diaphragm. Each rearward valve extension 183 has a small bleeder hole 198 communicating with both of its chambers 187 and 193, these bleeder holes being of such small diameter that after the closing of the flap valves 20 and 21 there will be a short delay, as about one second, before the pressures within the flap valve passages, hoses 22 and 23 and within both sets of chambers 187 and 193 are balanced at the reduced pressure produced by the pump P through the piping 194. When the same reduced pressure exists in the chambers 187, 193 at opposite sides of a diaphragm, this diaphragm is sufficiently dished to permit the valve 195 to drop to its bottom position and close the port 186 and allow atmospheric pressure from the port 185 to enter the cylinder 177 so that the spring 178 will urge the piston 176 into cylinder head engagement to present the latch pin in a yieldable latching position, as indicated by the position of the parts of the grinding feed controlling valve 25. The opening of one of the flap valves suddenly increases the pressure in one of the chambers 193 to atmospheric pressure causing an upward deflection of the diaphragm 188 which lifts the valve member 195 to its top position wherein the port 185 is closed and suction from the pump communicates through the now open port 186 with the cylinder to overcome the spring 178 and withdraw the piston so that the latch pin will be retracted from latching position, as indicated in Figure 1 by the positions of the parts of the grinding feed controlling valve 24.

In operation, a finished race ring A is mounted 45 on the ball type gauging head 30, and the rod 44 positions the valve lever 12 in accordance with the size of the finished raceway B. A race ring C, whose raceway R is to be automatically ground to matching relation with the raceway B, is mounted in grinding position while the stem 16 is raised out of operative position. At this time, the stud 92 is swung away from the transfer lever 18 and both flap valves 20 and 21 are closed. The suction pump P acting through the piping 194 and the bleeder holes 198 produces a balanced reduced pressure or a partial vacuum in both hoses 22 and 23 and in each pair of chambers 187, 193 causing both valve members 195 to assume their bottom positions wherein the ports 186 are closed and atmospheric pressure has access to both cylinders 177 through the open ports 185 so that the springs 178 shift both pistons 176 into cylinder head engagement to present the latch pins 130 and 131 in yieldable latching positions with respect to the latch plates 127 and 128. The handle 173 is lifted to reset the valve 143 in its illustrated operative position to start the grinding wheel oscillating. The upward movement of the valve stem 142 acts through the plate 154, bell crank 60 lever 156 and associated linkage to reset the lever 114 from its position 114B to its position 114A which shifts both of the oscillating pawls 102 and 103 into engagement with the ratchet wheel 100 to produce a coarse feed of the grinding wheel 70 14 towards and into the raceway R. The lever

73 is swung to its illustrated operative position to support the stem 16 on the raceway R.

When the coarse grinding wheel feed has ground the raceway R to a size determined by the preset position of the valve lever 12, the amplified linkage 83 and 84 and the transfer lever 18, controlled by the position of the stem 16, cause the screw 27 to open the flap valve 28 admitting atmospheric pressure through the hose 22 to suddenly increase the pressure within the chamber 193 of the valve 24, which causes the diaphragm to lift the valve member 195 to close the port 185 and open the port 186. Suction from the pump P through the port 186 now withdraws the piston 176 causing the latch pin 130 to disengage the latch plate 127 so that the lever 114 swings to its intermediate position (illustrated in full lines) determined by the engagement of the latch plate 128 against the latch pin 131, this intermediate lever position limiting the engagement of the pawls 102, 103 with the ratchet wheel 100 to change the coarse grinding wheel feed to a finish grinding feed.

When this finish grinding feed has further reduced the raceway R to a size predetermined by the position of the preset valve lever 12, the linkage operated by the stem 16 opens the flap valve 21 which admits atmospheric pressure through the hose 23 into the chamber 193 of the valve 25 causing its valve member 195 to shift to its top position. The suction from the pump P through the open port 186 withdraws the piston 176 of the valve 25 to retract the latch pin 131 from engagement with the latch plate 128, and the lever 114 swings to its position 114B which shifts both pawls 102, 103 away from the ratchet wheel to stop the finish grinding feed. Shifting of the lever 114 to its position 114B releases the pawl 144 into oscillated feeding engagement with the counting ratchet wheel 133, and the grinding wheel oscillation across the raceway R continues during grinding wheel sparking-out until the trip lug 150 on the preadjusted arm 152 releases the detent 135 causing the valve 143 to reverse and stop the grinding wheel oscillations. During the resetting of the valve 143 and of the lever 114, the detent 135 is lifted and the spring 134 returns the counting ratchet wheel to its starting position.

I claim:

1. In apparatus for controlling the grinding of an article to a size determined by the size of another article, gauging mechanism responsive to the reduction in size of the article being ground, a valve operated by the gauging mechanism, fluid pressure actuated means controlled by said valve for effecting a change in the rate of grinding, mechanism responsive to the size of the other article for adjusting the operative position of said valve, and means providing for a relative adjustment between the gauging mechanism and the valve to predetermine the size of the article at which said valve will be operated.

2. In apparatus for regulating the grinding to size of one of a pair of articles under control of the size of the other article, gauging mechanism responsive to the size of the article being ground, a valve operated by the gauging mechanism, fluid pressure actuated grinding controlling means controlled by said valve, and means controlled by the size of said other article for adjusting the control between said valve and said fluid pressure actuated grinding controlling means.

3. In apparatus for controlling the grinding to size of one of a pair of articles for mating re-

75

lation, gauging mechanism responsive to the size of the article being ground, a valve operated by the gauging mechanism, fluid pressure actuated grinding controlling means controlled by said valve to reduce the grinding operation when the article being ground is reduced to a predetermined size, a gauge for measuring the size of the other article, and gauge operated means to adjust the operative position of said valve with respect to said gauging mechanism.

4. In apparatus for regulating the grinding to size of one of a pair of articles under control of the size of the other article, gauging mechanism responsive to the reduction in size of the article being ground, a valve operated by the gauging mechanism, fluid pressure actuated means controlled by said valve for effecting a change in the rate of grinding, a gauge for measuring the size of the other of said articles and mechanism controlled by said gauge for adjusting the operative position of said valve with respect to the gauging mechanism.

5. In apparatus for controlling the grinding of an article to a size determined by the size of another article, gauging mechanism for measuring the size of the article being ground, a fluid pressure actuated grinding controlling device, a plurality of valves sequentially operated by said gauging mechanism for controlling said device, and means responsive to the size of the other article for adjusting the operative positions of the valves with respect to the gauging mechanism.

6. In apparatus for controlling the grinding to size of an article, gauging mechanism for measuring the size of the article during grinding, a feeding mechanism for a grinding operation, means for controlling the feeding mechanism and including a feed controlling lever movable to successive positions, latches regulating said lever movement, and fluid pressure actuated mechanism controlled by said gauging mechanism for operating the latches in accordance with the measured size of the article.

7. In apparatus for regulating the grinding to size of one of a pair of articles under control of the size of the other article, gauging mechanism responsive to the size of the article being ground, a grinding feeding mechanism, means for controlling said feeding mechanism and including a feed controlling lever movable to successive positions, latches selectively restricting the lever movement, fluid pressure actuated mechanism controlled by said gauging mechanism for selectively withdrawing the latches from said lever restricting position when the article is ground down to predetermined sizes, and means controlled by the gauging mechanism for returning the latches to their lever restricting positions when the gauging mechanism is removed from a gauging position.

8. In apparatus for controlling the grinding to size of one of a pair of articles under control of the size of the other article, gauging mechanism for measuring the size of the article being ground, a pair of valves interconnected by a duct, one of the valves being operated by the gauging mechanism to change the pressure within the duct, said other valve responding to a pressure change in the duct a grinding feed mechanism controlled by said other valve to effect a change in rate of grinding, and means responsive to the size of said other article and arranged to adjust the operative position of the gauging mechanism operated valve.

9. In apparatus for controlling the grinding to

11

size of an article, gauging mechanism for measuring the size of the article during grinding, a pair of valves interconnected by a duct, suction means for producing a less than atmospheric pressure in the duct, one of said valves being opened by the gauging mechanism to increase the pressure within the duct, said other valve responding to an increase in pressure in the duct, a grinding feed mechanism controlled by said other valve to effect a reduction in rate of grinding when the article is ground to a predetermined size, and means for adjusting the opening position of said first mentioned valve with respect to the gauging mechanism.

10. In apparatus for controlling the grinding to size of one of a pair of articles for mating relation, gauging mechanism for measuring the size of the article being ground, a pair of valves interconnected by a duct, one of said valves being operated by the gauging mechanism to change the pressure within the duct, said other valve responding to a pressure change in the duct to effect a reduction in rate of grinding when the article being ground is reduced to a predetermined size, a gauge for measuring the size of the other of said articles, and means operated by said gauge for adjusting the position of the gauging mechanism operated valve with respect to said gauging mechanism to control the size to which the article is ground.

11. In apparatus for controlling the grinding to size of one of a pair of articles for mating relation, gauging mechanism for measuring the size of the article being ground, a pair of valves arranged to be successively operated by the gauging mechanism when the article is respectively reduced to predetermined sizes, a gauge for measuring the size of the other of said articles, means responsive to said gauge to adjust the operating positions of said valves with respect to the gauging mechanism, and fluid pressure controlled grinding feed mechanism responsive to the operation of said valves.

12. In apparatus for controlling the grinding to size of an article, gauging mechanism for measuring the size of said article during grinding, a pair of valves arranged to be successively operated by the gauging mechanism, a pair of grinding feed controlling valves respectively connected by ducts to said first mentioned valves, said grinding feed controlling valves being respectively operated by fluid pressure changes in the ducts caused by the operation of the first mentioned valves, and means to adjust the operating positions of said first mentioned valves with respect to said gauging mechanism.

13. In apparatus for controlling the grinding to size of an article, gauging mechanism for measuring the size of said article during grinding, a pair of valves arranged to be successively opened by the gauging mechanism in response to the reduction in size of the article, means to adjust the opening positions of said valves with respect to the gauging mechanism, a pair of grinding feed controlling valves respectively connected by ducts to said first mentioned valves and operated by fluid pressure changes in the ducts caused by the opening of said first mentioned valves, and mechanism responsive to one of the feed controlling valves for reducing a grinding feed when the article is ground to a predetermined size and for further reducing the grinding feed when the article is reduced to another predetermined size.

14. In apparatus for controlling the grinding to size of an article, gauging mechanism for

12

measuring the size of the article during grinding, a self-closing valve connected by a duct to a grinding feed controlling valve, mechanism for reducing the pressure within the duct to less than atmospheric pressure when said self-closing valve is closed, the gauging mechanism being arranged to open the self-closing valve and increase the pressure within the duct when the article is ground down to a desired size, means to adjust the opening position of the self-closing valve with respect to the gauging mechanism, and means responsive to said grinding feed controlling valve for reducing a grinding feed when the pressure within the duct is increased.

15. In apparatus for controlling the grinding to size of an article, a gauging mechanism for measuring the size of the article during grinding, a grinding feed controlling valve having a pair of chambers, a member separating said chambers and moved by an unbalancing of pressures in said chambers, pressure controlling means for producing balanced pressures in said chambers, mechanism responsive to the movement of said member for reducing the rate of a grinding feed, and means actuated by the gauging mechanism for changing the pressure in one of said chambers when the article has been ground to a predetermined size.

16. In apparatus for controlling the grinding to size of an article, a gauging mechanism for measuring the size of the article during grinding, a grinding feed controlling valve having a pair of chambers, a member separating said chambers and movable in response to an unbalancing of pressures in said chambers, suction means for producing in said chambers substantially balanced pressures which are less than atmospheric pressure, mechanism responsive to the movement of said member for reducing the rate of grinding, and a valve operated by the gauging mechanism to unbalance the pressures in said chambers when the article is ground to a predetermined size.

17. In apparatus for controlling the grinding to size of an article, a gauging mechanism for measuring the size of the article during grinding, a grinding feed controlling valve having a pair of chambers, a diaphragm movable under control of an unbalancing of pressures in said chambers, means for producing in said chambers substantially balanced pressures which are less than atmospheric pressure, mechanism controlled by the movement of said diaphragm for reducing the rate of grinding, a valve opened by the gauging mechanism to increase the pressure in one of said chambers when the article is ground to a predetermined size, and means to adjust the opening position of said valve with respect to the gauging mechanism.

18. In apparatus for controlling the grinding to size of an article, a gauging mechanism for measuring the size of the article during grinding, a grinding feed controlling valve having a pair of chambers, a member separating said chambers and movable in response to an unbalancing of pressures in said chambers, mechanism responsive to the movement of said member for reducing the rate of grinding, said valve having a small passage between the chambers, suction means connected to one of said chambers and acting through said passage to produce in both chambers balanced pressures of less than atmospheric pressure, and a valve opened by the gauging mechanism to admit atmospheric pressure into the other of said chambers for unbalancing

said pressures when the article is ground to a predetermined size.

19. In apparatus for controlling the grinding to size of an article, a gauging mechanism for measuring the size of the article during grinding, a grinding feed controlling valve having a pair of chambers, a diaphragm separating said chambers and movable in response to an unbalancing of pressures in said chambers, mechanism controlled by a movement of said diaphragm for reducing the rate of grinding, said valve having a small passage between the chambers, a suction pump connected to one of said chambers and acting through said passage to produce less than atmospheric and substantially balanced pressures in both of said chambers, a normally closed valve arranged to be opened by the gauging mechanism for admitting atmospheric pressure into one of the chambers when the article is ground to a desired size, and means to adjust the opening position of said normally closed valve with respect to the gauging mechanism.

20. In apparatus for controlling the grinding to size of an article, a gauging mechanism for measuring the size of said article during grinding, a grinding feed controlling valve having a pair of chambers, a diaphragm separating said chambers and movable in response to an unbalancing of pressures in said chambers, suction means for producing substantially balanced pressures in said chambers, means responsive to said gauging mechanism for unbalancing said pressures when the article is ground to a predetermined size, fluid pressure actuated mechanism for controlling a grinding feed, said valve having a passage communicating between one of said chambers and the fluid pressure actuated mechanism, and a valve member operated by the diaphragm for opening and closing communication between said last mentioned chamber and said passage.

21. In apparatus for controlling the grinding to size of an article, a gauging mechanism for measuring the size of the article during grinding, a grinding feed controlling valve having a pair of chambers separated by a diaphragm movable in response to an unbalancing of pressures in said chambers, suction means for producing in said chambers balanced pressures which are less than atmospheric pressure, a device responsive to the gauging mechanism for unbalancing the pressures in said chambers when the article is ground to a predetermined size, fluid pressure actuated mechanism for controlling a grinding feed and communicating with a passage in the grinding feed controlling valve, said valve having a pair of ports respectively opening said passage to the atmosphere and connecting the passage to one of said chambers, and a valve member operated by said diaphragm for selectively closing said ports.

22. In apparatus for controlling the grinding to size of an article, a gauging mechanism for measuring the size of the article during grinding, a grinding feed controlling valve having a pair of chambers, a diaphragm separating said chambers and movable in response to an unbalancing of pressures in said chambers, a suction pump arranged to produce less than atmospheric and substantially balanced pressures in both of said chambers, a cylinder, a piston movable in said cylinder for controlling a grinding feed, said valve having a passage communicating between one of said chambers and said cylinder, a valve member operated by said diaphragm for opening and closing communication between said last

mentioned chamber and said passage, and means responsive to the gauging mechanism for unbalancing the pressures in said chambers when the article is ground to a predetermined size.

5 23. In apparatus for controlling the grinding to size of an article, a gauging mechanism for measuring the size of the article during grinding, a grinding feed controlling valve having a pair of chambers, a diaphragm separating said chambers and movable in response to an unbalancing of pressures in said chambers, said valve having a small passage between the chambers, suction means connected to one of said chambers and acting through said passage to produce in both chambers balanced pressures of less than atmospheric pressure, a cylinder, a piston normally urged to one end of the cylinder and moved within the cylinder in response to a change in pressure within the cylinder for reducing a grinding feed, said valve having a passage communicating with the cylinder, the valve also having a pair of ports respectively communicating from said passage to the atmosphere and to one of said chambers, a valve member normally closing communication between the passage and said last mentioned chamber, said valve being moved by the diaphragm to selectively close said ports, and a gauging mechanism operated valve for admitting atmospheric pressure into one of said chambers to cause a diaphragm movement.

24. In apparatus for regulating the grinding to size of one of a pair of articles for mating relation, gauging mechanism for measuring the size of the article being ground, a grinding feed controlling valve having a pair of chambers separated by a diaphragm which is moved by an unbalancing of pressures within said chambers, means responsive to the movement of the diaphragm for reducing the grinding feed, the grinding feed controlling valve having a small passage communicating between said chambers, a self closing valve connected by a duct to one of said chambers, suction means connected to said other chamber and acting through the passage to produce substantially equal and less than atmospheric pressures in both of said chambers, gauging mechanism operated means for opening the self closing valve to increase the pressure in said first mentioned chamber when the article is ground to the desired size, a gauge for measuring the size of the other article, and gauge operated means for controlling the opening position of the self closing valve with respect to said gauging mechanism.

55 25. In apparatus for regulating the grinding to size of one of a pair of articles under control of the size of the other article, gauging mechanism for measuring the size of the article being ground, fluid pressure controlling means operated by the gauging mechanism, grinding feed regulating mechanism responsive to the fluid pressure controlling means, and mechanism for measuring the size of said other article and arranged to adjust the operative relation between the fluid pressure controlling means and said grinding feed regulating mechanism.

26. In apparatus for regulating the grinding to size of one of a pair of articles under control of the size of the other article, gauging mechanism responsive to the size of the article being ground, fluid pressure controlling means regulated by the gauging mechanism, grinding feed regulating mechanism responsive to said fluid pressure controlling means, mechanism for measuring the size of the other article and arranged

to adjust the operative relation between the fluid pressure controlling means and the grinding feed regulating mechanism, and means providing for a relative adjustment between said gauging mechanism and the grinding feed regulating mechanism.

5 WILLIAM H. BLESSING.
